CHARLES J. AHRENFELDT, OF NEW YORK, N. Y.

DESIGN FOR A COVERED DISH OR SIMILAR ARTICLE.

SPECIFICATION forming part of Design No. 33,629, dated December 4, 1900.

Application filed November 10, 1900. Serial No. 36,133. Term of patent 7 years.

To all whom it may concern:

Be it known that I, CHARLES J. AHRENFELDT, a citizen of the United States, residing at the city of New York, county of New York, and State of New York, have invented and produced a new and original Design for a Covered Dish or Similar Article, of which the following is a specification, reference being had to the accompanying drawings, forming a part thereof.

In the said drawings, Figure 1 is a side view of a covered dish, showing my design. Fig. 2 is a plan of the same.

The body of the dish is of ovate form and is provided with a base B, which has a series of indentations B' in its periphery, giving it an undulated contour. From these indentations in the base furrows A extend upwardly to the rim of the body on slightly-divergent lines, giving the said body and rim an undulating appearance. A wave-like line of escalloped ornamentation C extends around the lower part of the body at the point where the base is joined thereto, and a series of small acorn-like ornaments D extends downwardly 25 therefrom.

The cover of the dish is divided into concave panels by the radial ridges E, extending from a point near the center to the rim thereof. The central part of the cover is surrounded by an elliptical ring of ornamentation, 30 similar to the ornamentations C D of the body.

The handles G at either end of the body and G' at the center of the cover are fluted 35 and have a band or collar g, with beaded ornaments in the center.

What I claim is—

The design for a covered dish or similar article substantially as herein shown and described.

Signed at the city of New York, in the county of New York, State of New York, this 14th day of March, 1900.

CHARLES J. AHRENFELDT.
